EXTENSIBLE CAMPER BODY

Joseph E. Oliver, Le Grand, Calif., assignor of ten percent to Lester J. Gendron, Madera, Calif.

Filed Oct. 1, 1964, Ser. No. 81,988

Term of patent 14 years

(Cl. D14—3)

FIG. 1

FIG. 2

FIG. 3

FIG. 4

FIG. 5

I claim:

The ornamental design for an extensible camper body, as shown and described.
